Atty.

UNITED STATES PATENT OFFICE.

JOHN FRASER, OF BRIGHTON, VICTORIA.

FUSE-LIGHTER.

SPECIFICATION forming part of Letters Patent No. 599,998, dated March 1, 1898.

Application filed July 6, 1896. Serial No. 598,088. (No model.) Patented in Victoria May 16, 1896, No. 13,100; in South Australia May 18, 1896, No. 3,253; in New South Wales May 19, 1896, No. 6,574; in Tasmania May 19, 1896, No. 1,614; in Western Australia May 29, 1896, No. 906; in England June 22, 1896, No. 13,746; in Germany June 24, 1896, No. 90,965; in Hungary June 27, 1896, No. 6,761; in South African Republic August 8, 1896, No. 1,178; in New Zealand September 9, 1896, No. 8,830; in Italy October 8, 1896, No. 42,809; in Belgium October 10, 1896, No. 123,929; in Switzerland October 12, 1896, No. 13,126; in France October 20, 1896, No. 260,566, and in India January 5, 1897, No. 194.

To all whom it may concern:

Be it known that I, JOHN FRASER, a subject of the Queen of Great Britain, and a resident of Malua street, Brighton, in the Colony of 5 Victoria, Australia, have invented certain new and useful Improvements in and Connected with Fuse-Lighters, (for which I have obtained Letters Patent in Great Britain, No. 13,746, dated June 22, 1896; in Germany, No. 90,965, 10 dated June 24, 1896; in Italy, No. 42,809, dated October 8, 1896; in France, No. 260,566, dated October 20, 1896; in Belgium, No. 123,929, dated October 10, 1896; in Hungary, No. 6,761, dated June 27, 1896; in British India, No. 15 194, dated January 5, 1897; in New Zealand, No. 8,830, dated September 9, 1896; in Western Australia, No. 906, dated May 29, 1896; in Tasmania, No. 1,614, dated May 19, 1896; in South Australia, No. 3,253, dated May 18, 20 1896; in New South Wales, No. 6,574, dated May 19, 1896; in Victoria, No. 13,100, dated May 16, 1896; in South African Republic, No. 1,178, dated August 8, 1896, and in Switzerland, No. 13,126, dated October 12, 1896,) of 25 which the following is a specification.

This invention has been devised to provide an inexpensive, efficient, and reliable means or appliance by which the fuses of explosives—such as dynamite, powder, or the like—may 30 be properly, regularly, and certainly ignited, and is designed to overcome many disadvantages attendant upon the modes or means at present in vogue for igniting such fuses. At the present time the fuses used in connection with explosives are usually lighted or endeavored to be lighted by what is called “spitting the fuse.” This method consists of holding a lighted flame to the end of the fuse until the latter spits fire. To enable the operator 35 to do this with a fair promise of safety, it is obvious that he must employ a long fuse. Otherwise he would not have sufficient time to reach a place of safety prior to the explosion taking place. When a number of fuses 40 are to be lighted, a difficult and precarious task has to be performed, inasmuch as the ordinary fuse will not ignite easily, and it 45 frequently happens that when the operator

succeeds in getting the first fuse to spit it extinguishes his light and for his own safety he 50 must precipitately abandon his task for a place of safety, leaving the other fuses unlit, or perhaps in his endeavors to light others of them he has left them in a smoldering condition only to explode some time after and possibly cause a serious accident. Another common way of igniting the fuse consists in bending it over somewhat in the form of an arch, keeping it in position by means of a stone or 55 lump of earth, and with a second lump of earth 60 or clay the operator affixes an improvised stand or candlestick under the arch, in which he places a lighted candle so arranged that the flame in a short time burns into the fuse if placed directly beneath same; but it happens in some cases, owing to varying conditions, such as wind or the distance of the 65 flame from the fuse, that the latter does not become properly fired, or in some cases to light at all, or in others the said fuse may 70 smolder for a considerable time and ignite more or less unexpectedly, and thus possibly cause accident. Moreover, an important feature in blasting or mining operations is to arrange the charges so as to explode in their 75 proper rotation—that is to say, in the direction calculated or aimed at by the experienced miner.

Now by the use of my invention the above difficulties and disadvantages are overcome, 80 and in order that my invention may be the more easily understood reference may be made to the accompanying drawings, in which—

Figure 1 is an elevation of my improvements 85 attached to a piece of fuse. Figs. 2 and 3 are also elevations of my improvements supplied with a protecting shield or hood, hereinafter to be referred to, part of Fig. 3 being in section. Fig. 4 shows a view of some minor details of 90 my invention, while Fig. 5 is a sectional plan taken at line *xx* on Fig. 4.

In the drawings, A represents a stem composed of a suitable freely igniting and burning material, hereinafter to be referred to, and 95 terminating in a bulb or enlarged portion B,

which is also composed of a suitable igniting chemical compound or material. Included in this bulb or enlarged portion B and depending therefrom is a small shank of wood, 5 wire, or other strong material. Encircled around or attached to this shank is a small coil of wire D, this latter wire D being for the purpose of attaching the shank C firmly to the fuse E and a little below the sliced portion E'. It will be noticed that the bulb or enlarged portion B is arranged so as to nestle in the slit portion E' of the fuse E.

Reverting to the wire D, it may in some cases be bent to form a depression, as D², and 15 then proceed upward and terminate either in a hook, as D', or a pointed end, as D³, so as to hold a hood, as G, or a cylinder, as H, provided with a cover, as H', in the position shown in Figs. 2 and 3. The said hood G or hooded 20 cylinder H is designed to protect my fuse-lighter while it is burning from drippings of water or drafts of wind; but where the tunnel or shaft in which my fuse-lighters are to be used is dry and not subject to drafts 25 the hood G or hooded cylinder H may be dispensed with. The material composing either G or H may consist of stiff paper, said paper having preferably been previously prepared with some preparation rendering it incom- 30 bustible.

Reverting to the stem A, I find that one suitable material for its composition consists of a mixture of chlorate of potash, five parts; sulfid of antimony, two parts; glue, one part, 35 with sufficient prepared vegetable meal to slacken the burning to the required travel per minute, and referring to the bulb or enlarged portion B, I find that one suitable material for its composition consists of a mixture 40 of chlorate of potash, thirty-two parts; of bichromate of potash, twelve parts; red lead, thirty-two parts; sulfid of antimony, twenty-four parts, with a little glue to consolidate the parts.

45 I do not confine myself to the employment of the compounds last set forth, as other suitable substances may be used in lieu thereof.

The material composing the stem A might in some cases be so calculated as to burn a 50 predetermined period before reaching and igniting the more fiery compound contained in the bulb B.

The *modus operandi* of my invention is as follows: The operator having arranged his 55 fuse for the explosion secures his shank C to the fuse E by a few tight twists of the wire D, having seen meanwhile that the bulb B is in close contact with a sliced portion E'. If the locality be a wet one, or exposed to drafts, 60 the operator may place the hooded cylinder H or hood G upon the wire D in manner shown on Figs. 2 or 3. He then lights the top of A, which being of highly-ignitable material, burns either quickly or slowly, but surely, 65 according to the character of the mixture of which it is composed, until the bulb B becomes ignited. This bulb being composed of a ma-

terial producing great heat and of great ignition power, quickly fires the fuse.

On Fig. 4 a plate or disk J, of cardboard or 70 analogous substance, is shown, its function being to act as a shield or plate, so as to prevent any sparks or ignited droppings from A touching or prematurely igniting either the bulb B or the slit fuse end E'. 75

I prefer in some climates to coat the outside of A and B with a film of gelatinous substance or varnish, so as to protect same from damp or deterioration.

I would here point out some of the advantages to be gained by using my improvements in connection with fuses, viz: (a) Economy is effected, inasmuch as shorter lengths of fuse can be used; (b) considerable reduction in the risk of misfires, thus saving loss of 85 time to workmen, who have to wait a given period before returning on the dangerous errand of ascertaining the reason of a non-explosion; (c) enabling the operator to light, say, three or more charges quickly with an 90 ordinary light, and should anything unforeseen arise during an interval of, say, three minutes which might prevent him retreating to a safe distance the said operator can simply snuff out the lighted stems and all danger is over, whereas under the present system 95 the unfortunate man or men would simply have to await their doom; (d) enabling shots to do their work properly by exploding in precalculated rotation, for by using my igniters and lighting them quickly the operator may with safety depend that all his fuses will be set on fire almost at the same instant, so that if the fuses are regulated in proper proportionate lengths the shots will explode in 100 correct rotation and do their best work; (e) the minimizing or avoiding of accidents or 105 catastrophes caused by quick fuses or premature explosions.

Having now particularly described and ascertained the nature of my said invention and in what manner the same is to be performed, I declare that what I claim is—

1. In a fuse-lighter, the combination with a stem of suitable freely-burning material, of a bulb or enlarged portion composed of a fiery compound and secured to said stem, a fuse having its end in close proximity to said bulb, a fastening-shank secured to the bulb and means for connecting the fuse to said shank. 115

2. In a fuse-lighter, the combination with a stem of suitable freely igniting and burning material, of a fuse having its end sliced, a bulb or enlargement secured to said stem near its lower end and composed of a suitable igniting material and arranged to nestle in the slit portion of said fuse, and means for securing the stem and fuse together. 125

3. In a fuse-lighter, the combination with a stem of suitable freely-igniting material and a bulb or enlargement secured to said stem near its lower end and also composed of a suitable igniting material, of a fuse with its end in close proximity to said bulb, a shank 130

of suitable material depending from said bulb, and a coil of wire serving to firmly attach said shank to the fuse.

4. In a fuse-lighter, the combination with a stem of suitable freely igniting and burning material and a bulb or enlargement secured to said stem near its lower end and also composed of a suitable igniting material, of a fuse with its end in close proximity to said bulb, means for securing the stem and fuse together, a protector for the fuse-lighter and means for supporting said protector in position.
5. In a fuse-lighter, the combination with a stem of suitable freely igniting and burning material and a bulb or enlargement secured to said stem near its lower end and also composed of a suitable igniting material, of a fuse with its end in close proximity to said bulb, a protecting-hood surrounding the fuse-lighter and provided with a cover H' and means for supporting said protecting-hood in position.
6. In a fuse-lighter, the combination with

a stem of suitable freely igniting and burning material and a bulb or enlargement secured to said stem near its lower end and also composed of a suitable igniting material, of a fuse with its end in close proximity to said bulb, a protector for the fuse-lighter and a wire D serving to secure the fuse and stem together and to support said protector in position.

7. In a fuse-lighter, the combination with a stem of suitable freely igniting and burning material and a bulb or enlargement secured to said stem near its lower end and also composed of a suitable igniting material, of a fuse with its end in close proximity to said bulb, and a shield or plate J on said stem and serving to prevent sparks or droppings from the stem prematurely igniting the bulb or fuse.

Signed this 15th day of April, 1896.
JOHN FRASER.
